UNITED STATES PATENT OFFICE.

CARL M. TJOSEVOLD, OF KRAMER, NORTH DAKOTA.

CHECK WRITER.

1,252,202.

Specification of Letters Patent.

Patented Jan. 1, 1918.

Application filed September 6, 1917. Serial No. 189,934.

To all whom it may concern:

Be it known that I, CARL M. TJOSEVOLD, a citizen of the United States, residing at Kramer, in the county of Bottineau and State of North Dakota, have invented a new and useful Check Writer; and I do hereby declare the following to be a full, clear, and exact description of the invention, such as will enable others skilled in the art to which it appertains to make and use the same.

This invention relates to an improved check writer, and an object of the invention is to provide a machine of this kind for filling or writing in the name of the payee and the amount of a check, draft or other instrument for transferring moneys.

A further object of the invention is the provision of a machine of this kind, by which the names, amounts and other descriptions may be written in deeds, mortgages, or in any such other instruments used for conveying of properties and the like.

A further object of the invention is the provision of a machine of this kind for use as aforesaid, whereby substantially absolute protection of all parties concerned is insured, and whereby alterations of such instruments of writing can be avoided, and should alterations be made detection is substantially absolutely insured.

A further object of the invention is to provide a machine of this kind involving a casing or frame in which a cylinder carriage is mounted, said carriage having a plurality of semi-shiftable type bands; in combination with means whereby selected type of the bands may be lined up for printing.

A further object of the invention is the provision of means for operating members adjacent certain selected type of the bands, whereby improved means such as will be hereinafter set forth may be operated to contact with said members for lining up certain selected type for printing.

A further object of the invention is the provision of means carried by said means for contacting with said members, for returning said bands to their initial positions by also contacting with the members.

A further object of the invention is the provision of means whereby an intermittent motion may be imparted to the cylinder carriage, whereby a semi-circular row of members adjacent the type of any band may

register with the means for operating the members, so that any pin adjacent a type to be selected on each band may be operated.

A further object of the invention is the provision of a platen roller for carrying the check or other paper or instrument to be printed provided with a movable segment section to bring the paper or check in contact with the lined up row of type in order to print the same.

A further object of the invention is the provision of means carried by the shaft of the platen roller and designed to engage a device on the cylinder carriage, to operate the segment section of the platen roller, whereby an impression of the lined-up type may be made on the check or other instrument carried by the segment section.

A further object of the invention is the provision of means for returning said members or pins, which are adjacent the type of the bands radially to their initial positions prior to making an impression of the type on the check.

In practical fields, the details of construction may necessitate alterations falling within the scope of what is claimed.

The invention comprises further features and combination of parts as hereinafter set forth and claimed.

In the drawings:—

Figure 1 is a plan view of the improved check writing machine constructed in accordance with the invention.

Fig. 2 is a sectional view on line 2—2 of Fig. 1.

Fig. 3 is a sectional view on line 3—3 of Fig. 1.

Fig. 4 is a front end view of the machine, showing the operating keys and the escapement mechanism.

Fig. 5 is a front end view of the check writing machine, showing the platen roller as having been operated, and the segment section of the roller in the act of making an impression.

Fig. 6 is a horizontal sectional view on line 6—6 of Fig. 2.

Fig. 7 is an enlarged detail perspective view of the spacer bar, and one of the keys or key bars, and the means to be actuated by one or the other of the spacer or key bar for actuating the escapement, to impart an intermittent motion to the cylinder carriage.

Fig. 8 is an enlarged detail view of a sec-

tion or portion of the cylinder carriage showing the spring tensioned members to be actuated for throwing or disposing pins adjacent selected type of said bands.

- 5 Fig. 9 is an enlarged detail view of a portion of the cylinder carriage, showing type bands having tongue and groove connections in the walls of adjacent channels of the cylinder carriage.
- 10 Fig. 10 is an enlarged detail plan view of the series of type bands of the cylinder carriage removed from the cylinder carriage, thereby showing the arrangement of type on the bands, and showing certain bands, as 15 having been operated in order to aline selected type for printing a name, as indicated at *a*.

Fig. 11 is an enlarged detail view of the means carried by the shaft of the platen 20 roller, for actuating a segment section of said roller.

Fig. 12 is a detail perspective view of the means carried by the cylinder carriage and 25 designed to be engaged by the segment section operating means.

Fig. 13 is an enlarged detail view in side elevation of the escapement mechanism.

Fig. 14 is an enlarged detail sectional view of the escapement means in Fig. 13.

- 30 Fig. 15 is a detail perspective view of the segment section of the platen roller.

Fig. 16 is an enlarged detail sectional view of a portion of the platen roller and a part 35 of the segment section thereof for carrying the check, which is designed to receive the impression.

Fig. 17 is a detail view showing the position of the segment section operating means, just before the segment section is operated.

- 40 Fig. 18 is a detail view showing the final position of the operating means of the segment section of the platen roller.

Referring more especially to the drawings 1 designates a frame or casing of the im- 45 proved check writing machine, and which frame may be any suitable construction, shape or configuration, preferably rectangular, and is provided with a forward extension 2, there being a divisional wall 3, di- 50 viding the forward extension from the major portion of the frame or casing. Mounted in bearings of the end 4 of the cas- 55 ing or frame and the partition or divisional wall 3 is a suitable guide rod or shaft 5, on which the shiftable cylinder carriage 6 is guided, whereby said carriage may be moved from one end of said casing to the other. Projecting from the partition or divisional wall is a skeleton frame 7, which comprises 60 the anchoring part 8, which merges into the arm 9 and the transverse part 10, the central portion of which is provided with a semi-circular curved part 11. The part 10 merges into an arm 12, which is substan- 65 tially in parallelism with the arm 9, as

clearly disclosed in Fig. 6. The rear ends of the arms 9 and 12 are connected by the semi-circular curved arch portion 13. Also connecting the arms 9 and 12 is a substantially U-shaped arch 14. The transverse 70 portion of the arch 14 is provided with a series of vertically disposed recesses or slots 15, in which a plurality of key bars 16 are pivotally mounted upon the rod 17. These key bars at their pivoted ends are provided 75 with upwardly extending right angle portions 18, while their forward ends have right angle portions 19, which are provided with finger pieces 20. As shown clearly in Fig. 1 these finger pieces are lettered accord- 80 ingly to the 26 letters of the alphabet, and the upper row of the finger pieces are numbered numerically, 1 to 9 inclusive. In order to cause the impression of the cipher, the key having the letter "o" thereon may 85 be employed. The cylinder carriage comprises the main cylinder 21, which, at points adjacent to and slightly below the diametric opposite sides of the cylinder, is provided with longitudinally extending bars 22. 90 These bars have ribs 23, which fit and are guided in the grooves 24 of the bars 25, which are in turn supported from the opposite longitudinal sides of the casing or frame, by virtue of the arms 26. Referring 95 more especially to Figs. 1, 2, 6, 8, and 9, it is to be noted that the outer circumference of the wall of the cylinder 21 is provided with a plurality of angular grooves 27. The opposite walls of each groove 27 are 100 provided with auxiliary grooves 28, and surrounding the wall of the cylinder 21 is a plurality of bands 29. Each band 29 is seated partially in its adjacent respective groove 27, and the opposite edges of said 105 band have ribs 30 engaging in the auxiliary grooves 28. As shown these bands are endless, and for a semi-circular portion of each band, its outer face is provided with the complete 26 letters of the alphabet which 110 are inter-spliced with numerals, from 1 to 9 inclusive, the letters being designated by the reference character 31, and the numerals by the reference character 32, the periods by the character 33, and the star type 34. 115 In order to employ or print a cipher, the letter "o" of the alphabet as indicated at 35 on each band is utilized. The wall of the cylinder 21 for a semi-circular portion thereof is provided with a plurality of openings 36, which, as shown in Fig. 8, are in the bottoms of the grooves 27. Mounted in the openings 36 are headed pins 37, the heads 38 of which are in the form of disks. Inter- 120 posed between the heads 38 and the inner surface of the wall of the cylinder 21 and surrounding said pins are coil springs 39. The outer extremities of said pins partially protrude into the grooves 27 and extending 125 transversely through the end portion of 130

each pin is a limiting pin 40, acting to prevent inward movement of the pins 37 radially. Each band is provided with a plurality of apertures 41, each of which receives a pin 42. These apertures alternate with the alphabetic and numerical characters, the purpose of which will be clearly obvious as the specification further progresses. The outer ends of the pins 42 are normally flush with the outer surface of each band. Each pin of each set of each band is provided with grooves 43 and 44. Carried by the inner face of each band 29 is a plurality of spring catches 45, each of which is secured at 36^a to its band. Each spring catch 45 is adjacent one of the pins 42, so that the nose or free end of the catch may engage one or the other of the annular grooves 43 and 44. When the nose or the free end of the catch is engaging the annular groove 43, the outer end of the pin 42 is held flush with the outer surface of the band, but when said nose or free end of the spring catch engages the groove 44, the pin 42 is held with its outer end portion projected beyond the outer surface of said band. To cause the outer end portions of the pins 42 to project beyond the band, it is necessary that pressure be applied against the head 38 of the pin 37, moving the same radially outwardly against the action of the spring 39. The purpose of so extending the pins 42 will be hereinafter disclosed. The rear face portion of the arch 13 is provided with a series of notches or recesses 47, corresponding in number to the notches, recesses or slots 15 of the U-shaped arch 14. Pivoted upon a curved rod 48 (which extends through the arch 13 and transversely of the recesses or notches 47) is a plurality of levers 49, there being one lever in each notch or recess. Each lever 49 comprises a short arm 50 which is angular and has a pin engaging portion 51 and the long arms 52. Connecting the long arms 52 of the levers 49 and the right angle extending portions 18 of the key bars 16, respectively, are rods 53. Interposed between the long arm 52 of each lever 49 and the crotch of the recess or notch 47 in close position to the pivot 48 is a spring 54, the action of which holds the angular arm 50 in contact with the crotch of the recess or notch 47, as shown at 55. It is to be observed that the pin engaging portion 51 of the lever 49 is designed at all times to assume a position adjacent one of the pins 37 of the cylinder carriage 6. Hence, when anyone of the keys 20 is depressed, its lever 16 is rocked upon its pivot 17, pulling upon the rod 53, thereby actuating the lever 49, so that the portion 51 of the lever 49 will cam against the head 38 and force the pin 37 radially outwardly against the action of the spring 39, thereby setting one of the pins 42. In other words,

one of the pins 42 is forced outwardly through its band, and held so extended by the nose of the free end of the spring catch 45 engaging the groove 44. For instance, should the key M of the keyboard 70 be depressed, the pin 42 adjacent the letter M of one of the bands will be moved outwardly, as previously set forth. For instance, the pin adjacent the letter M as indicated at a in Fig. 10. The period key of 75 the keyboard is then depressed, so as to move a pin 42 adjacent a period of one of the bands, as indicated in Fig. 10, outwardly. Then the key K of the keyboard is depressed, thereby causing a pin 42 adjacent the letter 80 K of one of the bands to be moved outwardly. The period key is again actuated after which the keys P, I and T are successively depressed (the key T being depressed twice in succession) whereby pins 42 adjacent such letters as PITT upon adjacent bands are moved outwardly. All the pins 42 that are thus actuated are carried by adjacent bands of the cylinder carriage 6, but, it is to be observed that such pins are not in 85 alignment when they are forced outwardly. However, to align said pins 42 and their adjacent letters to spell the name M. K. Pitt, means comprising a disk and the arms 57 and 58 is provided. The disk 57 is carried 95 by a sleeve 59, the interior surface of which is provided with an integral bearing collar 60 surrounding and movably mounted on the shaft or rod 5 which is held against rotation by its rectangular end 61 in a bearing of the 100 partition or wall 3. This sleeve or tubular member 59 is considerably larger in diameter than the shaft or rod 5, hence, its inner surface is spaced from said rod and its end portion opposite the collar 60 has a lug 62, 105 which is designed to engage the half spiral rib 63 of the rod or shaft 5, when the cylinder carriage is moved from the rear end of the frame or casing toward the forward end thereof, whereby a half turn may be imparted to the sleeve 59 and the disk and arm 110 57 and 58. This arm 58 is integrally carried by the sleeve 59. For instance, the arm 58 comprises the radial part 64, which merges into the loop 65, the curved arm 66 115 of which extends or curves from one side of the cylinder toward and to a point exteriorly of the cylinder, and its extremity 67 is connected to the disk 57 by means of a rod 68. This rod 68 extends across the surfaces of 120 the bands 29, as seen at 67 in Fig. 3. Where this rod 67 is located, the bands are provided with outwardly turned lugs 69, and when the bands are in their normal positions, these lugs 69 are aligned. As the various keys of 125 the keyboard are depressed, in order to extend the pins 42 adjacent the letters to spell the name M. K. Pitt, the cylinder carriage moves forwardly intermittently, but it does not necessarily reach its forward limit, and 130

to move it to its forward limit, it is necessary to overcome the escapement mechanism by forcing the cylinder carriage forwardly to its limit manually. When so moving the cylinder carriage, the lug 62 of the sleeve 59 contacts with the spiral rib 63 and imparts a half turn to the sleeve and the disk 57 and arm 58, and being t¹ at the rod 68 connects the disk and the arm 58, said rod 68 will contact with the several pins adjacent the letters of the name M. K. Pitt, and hence move the respective bands containing the letters of the name, whereby said letters are alined, as shown at *a* in Fig. 10. When the letters are so alined, the printing or impression of the name may be accomplished in the manner to be hereinafter stated. The skeleton frame 7 is constructed as previously set forth, in order to permit freedom of movement for the arm 58, and the arm 58 is constructed with the loop 65, so that when said arm is operated, as above set forth, the anchoring part 8 of said skeleton frame will enter the loop 65. The exterior portion of the sleeve 59 at its end having the collar 60 is provided with lugs 70, to which the springs 71 are connected. These springs are in turn connected at 72 to lugs of the partition or wall 3 of the frame or casing. The springs 71 serve to cause the revoluble return of the sleeve 59 and its disk 57 and arm 58, and also serve to draw the cylinder carriage from the rear portion of the frame or casing toward its forward portion, as the cylinder carriage is permitted to intermittently move, the escapement being intermittently released by the depression of the spacer bar 73 or the depression of any one of the key bars 16. However, when the sleeve 59 and its disk 57 and arm 58 are permitted to return revolubly to their initial positions, the rod 68 contacts with the several lugs 69 of the bands that have been moved in the manner previously set forth and causing the return of said bands to their initial positions. However, such bands are not returned to their initial positions until after the printing or impression of the type spelling said name M. K. Pitt. Mounted in bearings of the brackets 75 (which project laterally from one side of the casing or frame) is a shaft or rod 76, which also extends through the sleeve bearings 77 of the platen roller 78. This roller 78 is tubular, and its tubular part is connected by the spokes 79 to the sleeve bearings 77. Also extending radially from the sleeve bearings 77, are arms 80, in bearings of the outer ends of which the pintles 81 of a conventional form of gelatin or rubber inking roller 82 are mounted. The inner portions of the arms 80 have slots 83, in which the pintles 84 of the ink fountain roller 85 are mounted. This ink fountain roller may be of any conventional construction, preferably a hollow

cylinder having its wall perforated and carried by the outer surface of this perforated wall, is a suitable covering of felt or other suitable absorbent material 86. As the ink fountain roller rotates, incident to contact 70 with the ink roller 82, (which turns by engagement with the type) the ink on the interior of the cylinder 87, percolates through the small apertures or orifices, and is absorbed by the felt covering. This construction of inking mechanism may be varied. In order to permit of the mounting of the fountain and ink rollers in the manner shown, a section of the platen roller of the shape shown at 88 is cut away, for the reception of said roller. By virtue of the springs 89 bearing between the sleeves 77 and the pintles 84, (to which the outer ends of said springs 89 are swivelly connected) the ink fountain roller is, at all times, maintained in contact with the ink roller 82, hence feeding ink thereto, which in turn transfers it to the type of the bands of the cylinder carriage. The platen roller 78 has a segment section thereof cut from its wall, 90 and carried by one of the sleeves 77 is a radial arm 89^a, and carried by the segment section 90 that is cut from the wall of the platen roller at one end of said segment, is a radial arm 91, which is provided with a cylindrical bore 92 for the reception of the arm 89^a. By means of the springs 93 (which connect the segment section and one of the sleeves 77) the segment section 90 is held normally in the cut out portion of the wall 100 of the platen roller 78. The outer face of this segment section 90 is concaved, as shown, to conform to the outer curvature of the cylinder carriage, and this concaved surface of the segment section is provided with longitudinal serrations 94, so that when the surface is brought into contact with the type of said bands of the cylinder carriage, portions of the impression of the type will be heavier than other portions and vice 110 versa, and at the same time cause an irregularity in the paper. Hence, by this construction the printing of the name of the payee of a check or other instrument will be very difficult to obliterate, as well as being difficult to alter the amount of the check or other instrument. In fact, the serrations 94 are formed on a face plate, and the opposite longitudinal portions of this face plate have extension flanges 95 and 96, which seat in recessed parts 97 of the wall of the roller 78. The edge of the flange 95 at its ends is provided with hinged spring clips 98, which are designed to engage the check or other instrument near its longitudinal edge portion, while the single elongated spring clip or hinged plate 99 (which is carried by the extension flange 96) engages the check or other paper near its opposite edge portion, thereby detachably connecting the check or 120 125 130

the like to the segment section of the platen roller. On one end of the platen roller, a handle 100 is provided, and by grasping this handle, the roller 78 may be turned substantially 5 a half revolution, in order to bring the segment section and the check or other paper carried thereby opposite the lined up type of the cylinder carriage. On one end of the cylinder carriage, the end nearest the keyboard, an arched member 101 is supplied. Threaded in the side wall of the member 101 is a screw 102, and swiveled on its inner end is a spring plate 103. The arm 91 of the segment section 90 is provided with a head or enlargement 104 which has an inclined or angular edge 105. When the platen roller is rotated a half revolution in order to bring the segment sections opposite the lined up type, the head or enlargement 104 of the arm 91 so enters the member 101 that the inclined or angular cammed edge 105 will cam upon the spring member or plate 103, thereby pulling the segment section of the platen roller from its corresponding 15 shaped pocket against the action of the springs 93. The arm as it approaches the member 101 slides against the end of the cylinder carriage with sufficient closeness that both ends of the segment section will move from its pocket uniformly, and as it is moving outwardly, it is at all times maintained in true parallelism with the cylinder carriage so that the complete line of type will make a full impression. By adjusting 20 the set screw 102, it is to be noted that the impression on the type or on the paper may be increased or decreased. The platen roller 78 adjacent the inking roller is provided with a longitudinally extending protruding rib or bulge 106, which will tend to contact with lined up pins 42 and return them radially to their normal positions so that the noses of the spring catches 25 will engage the groove 43. The object in so returning said pins, whereby their outer ends are flush with the outer faces of the bands, is to enable the inking roller to freely pass and contact with the type, and to allow the check or other instrument carried by the face plate of the segment section to receive a true and proper impression of the type. The bottom of the casing or frame is provided with a longitudinal groove 107 extending substantially the full length of the frame or casing. Carried by the cylinder carriage 6 is an elongated bar 108, which has its opposite ends connected to the bottom portion of the ends of said cylinder carriage. By this construction and arrangement 30 of the bar 108 and the corresponding connections for the bars 22, said bars 108 and 22 intermediate their ends, arch over the bands (half of their circumference being without type), so as to permit freedom of movements of the bands and avoid any obstruction to the type on the bands when they are moved for lining up the type for printing. The bar 108 enters the longitudinal groove 107 of the casing or frame and acts as additional means to guide and steady the cylinder carriage when moved longitudinally. The under surface of the bar 108 is provided with rack teeth 109. At a suitable selected point of the bottom of the casing or frame a suitable slot 110 is formed. Secured at 111 to the bottom of the casing or frame is a bracket arm 112, and mounted in a bearing 113 thereof, is a shaft 114, having a head 115 at one end and a nut 116 fixed on its opposite end. Loose upon the shaft 114 is a drum 117, which has an annular flange 118 provided with gear teeth 119. Secured or fixed by virtue of a pin 120 on the shaft 114 is a gear 121, the marginal edge portion of which protrudes through the slot 110 in the bottom of the casing or frame, whereby its teeth may mesh with the rack teeth of the bar 108. When operating this improved check or document printing machine, the cylinder carriage is normally positioned at the rear end of the frame or casing. Secured by a screw 122 to the shaft 114, is one end of a comparatively strong spiral spring 123, the other end of which is secured by a screw or the like 124 to the inner wall of the drum 117. The spring 123 is so wound, that it is put under tension, in fact tightened, as the cylinder carriage moves intermittently from the rear end to the forward end of the casing or frame. Even though the spring 123 is put under tension and tightened as the carriage so moves, its tension or tightness at any time does not exceed the tension of the springs 71, for, by virtue of the springs 71, the cylinder carriage is drawn forwardly, when allowed to move intermittently, the same having been released by the escapement, in fact, intermittently released. The main purpose of the spring 123 is to assist the operator in returning the cylinder carriage manually to its initial position at the rear of the casing or frame. Mounted upon a stud 125 which is headed, as shown at 126, is a dog 127, the nose of which enters between any two teeth 119 of the flange 118. By disengaging the dog from the teeth 119 of said flange 118, the drum 117 may be turned or adjusted in one direction or the other, for tightening or loosening the spiral spring 123. Should the spring 123 be increased in its tension, greater assistance will be given the operator in returning the cylinder carriage to its initial or starting positions. In order to turn or rotate the drum 117, when the dog is released, a handle or member 128 is carried by the flange 118, and it is clearly obvious, by grasping said handle, as to how the drum may be adjusted. One end of the hub of the gear 121 is pro-

100

105

110

115

120

125

130

vided with diametrically oppositely disposed clutch teeth 129, and loose on the shaft 114, is a ratchet wheel 130, provided with a hub 131 having diametrically opposite disposed clutch teeth 131 to coöperate with said clutch teeth 129. A suitable washer 132 is mounted on the shaft 114 adjacent the ratchet wheel 130, and interposed between the washer and the nut 116 and surrounding the shaft 114, is a coil spring 133, its purpose being to bear against the washer and maintain the clutch teeth 129 and 130 in engagement, in fact not too positive but enough, so that the ratchet wheel and gear wheel 121 will rotate together, yet at the same time when sufficient force is applied on the carriage, such positive engagement of the clutch teeth as insured by the spring may be overcome, and the carriage may be moved longitudinally of the frame manually. Mounted in guide apertures 134 of the bottom of the extension 2 of the frame or casing is a U-shaped member 135 to the upper ends of the arms of which a transverse rod or bar 136 is integrally connected. Suitable springs 137 are interposed between the rod 136 and the bottom 138 of said extension 2 of the frame or casing, said springs surrounding the arms of the U-shaped member 135. This transverse rod or bar 136 is so arranged transversely of the extension 2 as to hold the arms 139 of the spacer bar 73 and the keybars 16 in their highest raised positions. Integrally connected to the crotch portion of the U-shaped member 135 and extending rearwardly is a rod 140. The rear end portion of this is pivoted at 141 on a lug 142 depending from the bottom of the casing or frame 1. The extremity of the rod 140 has pivoted thereon at 143 a pawl 144, under tension of the spring 145, whereby the nose or the free end of the pawl is maintained at all times in contact with the teeth of the ratchet wheel. Also pivoted at 141 on the lug 142 is a pawl or dog 146, the nose of which remains, at all times in contact with the teeth of the ratchet wheel 130, owing to the gravitation of the pawl or dog. When the spacer bar or any one of the key bars is depressed, the same contacts with the transverse rod 136, thereby depressing the U-shaped member 135, hence tilting the rod 140 on its pivot. Thus it will be seen that the rear extremity of the rod 140 will move upwardly and the nose of the pawl or dog 144 will pull upon the ratchet wheel and impart a step by step movement thereto, and since the ratchet wheel rotates with the gear 121 through the medium of the clutch teeth 129 and 131, a corresponding step by step movement is imparted to the cylinder carriage. By virtue of the pawl or dog 146, backward movement of the ratchet 130 is prevented. It is to be noted that the tension of the spring 133 is to be such that, the tension of the spring 123 will be so much greater as to overcome the spring 133 and cause the clutch teeth 129 and 131 to disengage and move the cylinder carriage rearwardly, this however is largely overcome owing to the tension of the springs 71. It is obvious, though, that by applying sufficient manual pressure on the cylinder carriage, the coöperation or engagement of the teeth 129 and 131 may be overcome and the cylinder carriage moved in one direction or the other independently of its controlling means. The frame or casing of the machine is provided with suitable supporting legs 147 having buffer ends 148, whereby the casing may be supported to avoid obstruction to the escapement mechanism which depends from the bottom of the casing.

As shown the serrations 94 of the segment section 90 of the platen roller are not of a greater width than the height of the letters of the bands of the cylinder carriage, whereby the serrations will properly register with the letters and figures or other characters of the bands of the cylinder carriage, when said characters are arranged in a printing line. The letters and the figures or other characters, in fact the type of the bands of the cylinder carriage are also provided with serrations 94^b. By constructing the serrations 94 of less width, or the same width as the height of the letters and providing serrations on the type the said serrations 94 of the segment section 90 of the platen roller will contact with no other part of the check or document above and below the type of the printing line thereby preventing mutilation of the document or check, where printing on the check is unnecessary. On account of the different widths of different checks, it is necessary to establish an indicating line, for instance as shown at 94^c, in fact the lowermost serration 94 of the segment section 90 of the platen roller, and when inserting the check or document to be printed, the line on which the printing is to be accomplished, in fact on which the impression is to be made, should be aligned or registered with the indicating line 94^c. In order to permit the check or document to be adjusted, whereby the point or the line where the impression is to be made can be adjusted to the indicating line 94^c, the spring clip or hinge plate 99 is provided with an opening 99^a, to permit the check or document to pass therethrough, and the clips 98 are provided with arms 98^a to overlie the check or document to hold the same in place. By this arrangement the document or check may be so spaced or adjusted, whereby the line or the point where the impression is to be made may be adjusted or arranged in registration with the indicating line, thus

making the impression at the proper point, regardless of the width of the check or the document, and by this arrangement of clips, the check or document may be adjusted in order to space the name of the payee from the amount.

The invention having been set forth, what is claimed as new and useful, is:—

1. In a printing machine, a cylinder, annular type carrying members movably surrounding the same, and means for imparting longitudinally intermittent motion to the cylinder and pre-determinedly selecting certain type of said members.
2. In a printing machine, a cylinder, annular type carrying members movably surrounding the same, and means for imparting longitudinally intermittent motion to the cylinder and pre-determinedly selecting certain type of said members, and means for lining up said selected type.
3. In a printing machine, a printing cylinder, annularly movable type carrying elements thereon carrying devices to be actuated radially outwardly, whereby certain type are selected, means carried by the cylinder to contact with said devices for lining up the selected type opposite an impression member, and means for returning said devices to their initial position.
4. In a printing machine, a cylinder, movable elements having type and surrounding the cylinder, said elements having devices to be actuated radially outwardly, whereby certain type may be selected, means to engage said devices for moving the elements for bringing the selected type to a printing line, an impression member, and co-operative means carried by the member and the cylinder respectively, whereby the impression member is brought into contact with the lined up type.
5. In a printing machine, a cylinder, movable elements having type and surrounding the cylinder, said elements having devices to be actuated radially outwardly, whereby certain of said type may be selected means to engage said devices for moving the elements for bringing the selected type to a printing line, an impression member, and co-operative means carried by the member and the cylinder respectively, whereby the impression member is brought into contact with the lined up type, and means carried by the impression member to return said devices to their initial position prior to an impression of the member on the type.
6. In a printing machine, a cylinder, movable annular elements surrounding the same and having type, devices to be actuated and carried by the elements for selecting certain type, means on which the cylinder is longitudinally guided, means for moving the cylinder longitudinally, means within the cylinder circumferentially movable on the guiding means for engaging said devices for lining up said selected type.
7. In a printing machine, a cylinder, a plurality of circumferentially movable elements thereon and provided with type, devices to be actuated to select certain type, and circumferentially movable means to engage said devices to move the elements to line up the selected type.
8. In a printing machine, a longitudinal shiftable cylinder, elements circumferentially movable thereon and provided with type, devices carried by the elements, setting means to set the devices to select certain type, and circumferentially movable means movable with the cylinder to engage the devices for moving the elements, whereby the selected type are lined up.
9. In a printing machine, a longitudinal shiftable cylinder, annular elements circumferentially movable and surrounding the cylinder and carrying type, devices carried by the elements and adapted to be set to select certain type, and a circumferentially movable member movable with the cylinder to engage the devices to move the elements, whereby the selected type are lined up.
10. In a printing machine, a plurality of circumferentially movable and individually movable elements axially concentric with each other and provided with type, a longitudinal movable carrier for said elements, devices carried by the elements and adapted to be set to select certain type, and circumferentially movable means carried by the cylinder to engage the devices and move the elements, whereby selected type are lined up.
11. In a printing machine, a plurality of semi-movable annular elements having type, a carrier therefor, devices adapted to be set to select certain type, and a semi-movable member to contact with the respective devices for moving the elements, whereby the selected type are lined up.
12. In a printing machine, a cylinder, elements circumferentially movable thereon and provided with type, devices carried by said elements, a frame having guides for said cylinder, a shaft mounted in the frame, and means movable longitudinally on the shaft and shiftable with the cylinder and being rotatable on the shaft, and means of connection between the longitudinally movable means and the shaft, whereby said longitudinally movable means may be partially rotated, said longitudinally movable means having a member to engage said devices for moving the elements whereby selected type are lined up.
13. In a printing machine, a frame, a guide shaft mounted therein, a printing cylinder through which said shaft concentrically extends, said frame having guides for

the cylinder, said cylinder having annular grooves, the bottoms of the grooves having spring tensioned pins, annular bands provided with type mounted for circumferential movement in guides of said grooves, devices carried by the bands between the several type, and means for moving the cylinder longitudinally, and means for actuating each individual spring tensioned pin, which in turn actuates said device for selecting certain of said type on the cylinder.

14. In a printing machine, a longitudinally movable printing cylinder provided with annular grooves having guides, circumferentially movable bands having type mounted in the guides of the grooves, said bands having devices adapted to be actuated for selecting certain type, spring tensioned pins, each alined with one of said devices, and means to be manually actuated to engage and operate any one of the spring tensioned pins for actuating any one of said devices, whereby selected type may be indicated.

14. In a printing machine, a longitudinally movable printing cylinder provided with annular grooves having guides, circumferentially movable bands having type mounted in the guides of the grooves, said bands having devices adapted to be actuated for selecting certain type, spring tensioned pins, each alined with one of said devices, and means to be manually actuated to engage and operate any one of the spring tensioned pins for actuating any one of said devices, whereby selected type may be indicated, and circumferentially movable means to engage said devices, whereby the selected type may be lined up.

16. In a printing machine, a longitudinally movable printing cylinder provided with annular grooves having guides, circumferentially movable bands having type mounted in the guides of the grooves, said bands having devices adapted to be actuated for selecting certain type, spring tensioned pins, each alined with one of said devices, and means to be manually actuated to engage and operate any one of the spring tensioned pins for actuating any one of said devices, whereby selected type may be indicated, and circumferentially movable means to engage said devices, whereby the selected type may be lined up, guides for the cylinder, means for moving the cylinder longitudinally, a manually rotatable impression cylinder having an impression member, an element carried by the printing cylinder, means carried by the impression member and adapted to engage said element when the impression member is rotated for bringing the impression member with the paper thereon toward the lined up type, and means

carried by the impression cylinder for returning all of said devices to their normal position prior to bringing the impression member opposite the lined up type.

17. In a printing machine, a cylinder provided with circumferentially movable type carrying members, a key board, any one of the keys of which adapted to move the cylinder longitudinally, selector means carried by the type bands, and means also actuated by the keys simultaneously with the movement of the cylinder for selecting certain type.

18. In a printing machine, a cylinder, a plurality of circumferentially movable elements carrying type and type selector means, devices carried by the cylinder for actuating the selector means, and a key board, any one of the keys of which adapted to move the cylinder longitudinally and actuate said devices simultaneously.

19. In a printing machine, a cylinder, a plurality of circumferentially movable elements carrying type and type selector means, devices carried by the cylinder for actuating the selector means, and a key board, any one of the keys of which adapted to move the cylinder longitudinally and actuate said devices simultaneously, and means circumferentially movable and adapted to contact with the selector means for lining up the type on a printing line.

20. In a printing machine, a printing cylinder, a plurality of type carrying elements circumferentially movable thereon, selector means for the type, devices to actuate the selector means, means to actuate the devices, and means whereby certain predeterminedly selected type may be lined up opposite an impression member.

21. In a printing machine, a cylinder having annular grooves, type carrying elements circumferentially movable in said groove, type selector devices carried by the elements, and means in the bottom of the grooves adapted to be actuated to operate the devices.

22. In a printing machine, a printing cylinder, means to move the cylinder longitudinally on its axis, a plurality of type carrying elements circumferentially carried on the cylinder, means to be actuated to select certain of said type, and a device having connections with the cylinder and given a circumferential movement incident to a longitudinal movement of the cylinder to engage the selector means and line up the selected type.

23. In a printing machine, a printing cylinder having a plurality of guides, circumferentially movable members mounted in said guides and having type, selector pins for said type, and a plurality of spring tensioned devices carried in said guides and by the cylinder to actuate the respective pins.

24. In a printing machine, a printing cylinder having a plurality of guides, circumferentially movable members mounted in said guides and having type, selector pins for said type, and a plurality of spring tensioned devices carried in said guides and by the cylinder to actuate the respective pins, and means consisting of a plurality of keys, any one of which adapted to actuate one of said devices and impart an intermittent motion to the cylinder simultaneously with the movement of the device.

25. In a printing machine, a cylinder, a plurality of circumferentially movable elements thereon and having type adapted to be lined up to a printing line, a roller provided with a radially movable impression segment, spring tensioning means therefor, and means to move the segment radially toward the printing line.

26. In a printing machine, a printing cylinder having a printing line of type, camming means on one end of the cylinder, a platen roller provided with a radially mov-

able tensioned impression segment, and means carried by the segment to engage the camming means to move the segment toward the printing line.

27. In a printing machine, a printing cylinder, type carrying elements thereon, selector means for the type, a guide having a cam, and means mounted on the guide and given a circumferential movement by the cam to engage the selector means to align the type.

28. In a printing machine, a printing cylinder, type carrying elements circumferentially movable thereon, selector means for the type, and means circumferentially movable for coördinately engaging the selector means and collectively lining up the type.

In testimony whereof I have signed my name to this specification in the presence of two subscribing witnesses.
